UNITED STATES PATENT OFFICE.

FRIEDRICH PIESSLINGER, OF PHILADELPHIA, PENNSYLVANIA.

BEATER-ROLL WITH VENTILATED KNIFE-CELLS.

No. 829,229.

Specification of Letters Patent.

Patented Aug. 21, 1906.

Application filed July 7, 1905. Serial No. 268,695.

To all whom it may concern:

Be it known that I, FRIEDRICH PIESSLINGER, a citizen of the Austrian-Hungarian Empire, residing since June, 1905, at Philadelphia, in the county of Philadelphia, State of Pennsylvania, have invented a new and useful Beater-Roll with Ventilated Knife-Cells, of which the following is a specification.

10 My invention relates to an improvement in beater-rolls, which can be applied to all rolls, as used in any system of beater, to beat or to cut paper-stock, material for making paper, or boards or pap-like substances; and the object of my improvement is to construct the beater-rolls in such a manner that the air filling the knife-cells (spaces between the knives) can leave each knife-cell not only on the two ends or shoulders of the roll, but on 15 one or more points between the ends or shoulders of the roll, when the knife-cells plunge into the liquid or pap-like stock.

A further object of my invention is to so construct a beater-roll that it is provided 25 with short knife-cells, each one of said knife-cells extending over only a part of the entire length of the roll, so that when the knife-cells plunge into the pulp the air being expelled by the pulp can escape on both ends of the 30 short knife-cells.

Further objects and advantages of the invention will hereinafter appear and the novel features thereof will be specifically defined by the appended claims.

35 The invention is clearly illustrated in the accompanying drawings, which, with the numerals of reference marked thereon, form a part of this specification, and in which—

Figure 1 represents a front elevation of a 40 beater-roll embodying my invention. Fig. 2 represents a sectional elevation of another embodiment which may be employed.

In both the embodiments shown the knives may be set parallel or in any angle to the axis 45 of the roll or may be formed in any line, as they are already formed in serpentine or other lines.

Similar numerals of reference indicate corresponding parts in the figures.

50 Referring to the drawings, 1 designates the roll-axis, having mounted thereon sectional roll-bodies 2 in any suitable manner.

3 designates knife-blades, which in Fig. 1 are shown as extending to the edge of the body-sections.

In the embodiment shown in Fig. 2, 4 designates the shaft on which the sectional roll-bodies 5 are mounted, said sections 5 having knives 6 secured thereon by means of shrunk rings 7 engaging the apertures or slots 8 at 55 the ends of said knives, it being noted that the ends of the knives in this instance terminate at a point within the ends of their body-sections.

In use the axis of the beater-roll is always above the surface of the stock and 60 the roll can be rotated with less power in proportion to the speed. The air passes from 65 the air-spaces between the blades through the passages formed between the sets of blades, said sets being in alinement, angularly disposed, or in staggered relation to each other.

The direction of the air passing from the blades is in every case substantially circumferential and not axial, as has heretofore been proposed. By reason of the high 70 angle of the blades the beater-roll can not only be actuated at a higher speed in proportion to the power employed, but the speed of circulation of the stock is increased.

As the air does not hinder the liquid or stock from filling the cells, the cells can be made much smaller than on a beater-roll as heretofore 75 constructed, and a roll embodying the improvements herein described and having the same diameter as one constructed according 80 to the ordinary type will do the same beating with a much lower speed and also save power, since there are more knives on the roll-body.

The stock circulates much quicker, and time will therefore be saved in beating the same 85 quantity of stock, as is evident. Better circulation of the stock will also be obtained by 90 a quicker and more exact discharge of the ventilated knife-cells. It will be apparent that while in Fig. 2 the knives have been 95 shown in alinement, whether these knives are in or out of alinement depends entirely upon the manner in which the sectional bodies are assembled.

What I claim as my invention, and desire 100 to secure by Letters Patent, is—

1. In a beater-roll, a sectional roll-body, knives carried by each section and arranged out of alinement when said sections are in

assembled position providing air-passages for the circumferential escape of air at one or more points between the adjacent ends of the knives.

5 2. In a beater-roll, a sectional roll-body, knives having a slot at each end carried by each section, the inner end of each knife terminating at a point within the end of their body-section, and shrunk rings seated in said

slots for retaining said knives in fixed relation to said body.

In testimony whereof I affix my signature in presence of two witnesses.

FRIEDRICH PIESSLINGER.
